FITTING

Angelo Minella, Boston, Mass.

Application March 26, 1937, Serial No. 133,196

6 Claims. (Cl. 285—210)

This invention relates to pipe fittings and more particularly, although not exclusively, to a fitting for connecting a feed pipe from the main supply pipe to a radiator in a one pipe hot water heating system and for connecting a return pipe line from the radiator to the main supply pipe, i. e. a reversible fitting.

In a one pipe hot water heating system a single main supply pipe extends from the heater to a location adjacent each radiator and thence back to the heater. Separate branch supply and return pipes are connected between the main supply pipe and each radiator. Prior to the present invention one pipe hot water heating systems have possessed many objectionable features. In such systems it has been impossible to obtain satisfactory circulation without using a pump or other artificial circulator. Even with such circulators satisfactory distribution and equalization of heat could not be obtained and radiators closest to the heater would utilize the heat almost to the exclusion of the radiators most remote from the heater.

Prior to the present invention the only satisfactory hot water heating systems have been the two-pipe systems, that is, with one pipe supplying hot water to the radiators and one pipe returning the water to the heater. These two-pipe systems are expensive to install and cost about one-third more than the installation of a steam heating system. Therefore, in instances where cost has been a principal factor, a steam heating system has been installed in preference to a hot water heating system.

The present invention makes possible an efficient one-pipe hot water heating system in which there is an even distribution of hot water to all radiators. This is made possible by a special pipe fitting for connecting both the branch supply pipes and return pipes to the main supply pipe, i. e., the fitting is reversible. The fitting of the invention tends to maintain well defined hot and cold water regions throughout the main supply pipe. Thus, as the water passes into the fitting, hot water is conveyed from a portion only of the hot water region leaving the remaining portion of the hot water region for the passage of hot water through the fitting. When the water is returned from a radiator to the main pipe, it is caused to flow into the cool water region of the main pipe. Consequently, well defined hot and cool water regions are maintained throughout the main supply pipe so that the temperature drop throughout the length of the main supply pipe is

not great and water at desired high temperature is supplied to all radiators.

The invention will be more clearly understood from the following description in conjunction with the accompanying drawings, in which:

Fig. 1 is an elevational view of a portion of a hot water heating system employing a fitting embodying the invention;

Fig. 2 is a sectional view taken upon the line 2—2 of Fig. 1;

Fig. 3 is a sectional view taken substantially upon the line 3—3 of Fig. 2;

Fig. 4 is a sectional view taken upon the line 4—4 of Fig. 3;

Fig. 5 is a sectional view taken upon the line 5—5 of Fig. 1;

Fig. 6 is a sectional view taken upon the line 6—6 of Fig. 5;

Figs. 7, 8 and 9 are diagrammatic views illustrating several positions in which the fitting may be used for connecting the main supply pipe with the branch supply pipe returning to the radiator;

Fig. 10 is a diagrammatic view illustrating the same fitting positioned to connect the return pipe from the radiator to the main pipe.

Fig. 11 is a plan view of a fitting of modified construction;

Fig. 12 is an end elevational view as viewed from the right of Fig. 11; and

Fig. 13 is a longitudinal sectional elevational view.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

A fitting embodying the invention is illustrated in the accompanying drawings at 10 and may be employed either for connecting the supply pipe 30 to a radiator 31 with the main supply pipe 32 of a one pipe hot water heating system as shown at A in Fig. 1 or may be employed for connecting the return pipe 33 from the radiator to the main pipe 32 as shown at B. The fitting 10 comprises a body 11 having a main passage 12 which is provided with internal threads 13 at each end to receive a pipe connection. The body 11 is provided with an elbow formation 14 having a por-

tion 9 extending laterally from the body and a wall portion 15 projecting into the passage 12. The elbow formation provides a branch passage 16 the outer end of which is internally threaded to receive a pipe connection. The inner end of the passage 16 faces one end of the main passage and is located adjacent the wall of the main passage and occupies a portion of the cross sectional area of the main passage 12 which is not greater than the difference between the cross sectional areas of the main passage 12 and the passage in the main pipe 32. Preferably, the elbow formation 14 is located so that the center line of the branch passage 16 lies in a plane spaced from 15 and parallel to the center line of the main passage 12. The wall portion 15 of the elbow formation 14 curves and extends toward one end of the fitting to a point opposite the portion 18 of the body 11 and viewed exteriorly as shown in 20 Figures 3, 4, 6 and 7 to 10, the wall portion 15 is composed of angularly disposed walls within the bore of the fitting which merge into the wall thereof. These walls as shown are substantially of a length less than the radius of the bore of 25 the fitting. The portion 18 is shaped to form part of the wall of the elbow formation and is curved transversely as shown in Fig. 4 and is inclined longitudinally from near one end of the fitting outward toward the outer end of the elbow formation as shown in Fig. 3. Consequently, the 30 entrance or mouth 20 of the branch passage 16 is not choked.

As illustrated in Fig. 1 the fitting A is arranged so that the mouth or inner end 20 of the elbow 35 formation is positioned in the upper or hot water region of the pipe 32 and faces in the opposite direction from that indicated by the arrows to permit the hot water to flow into the branch passage 16 and at the same time permit a portion 40 of the water in the hot water region to flow through the fitting A. As shown at B the fitting 10 is turned in the opposite direction from its position as shown at A and is turned 90° about its axis so the inner end 20 of the elbow formation 45 is positioned in the lower or cold water region of the pipe 32 and faces in the same direction as the arrows. In other words, the fitting is reversible.

As shown in Fig. 2, the elbow formation 14 is 50 offset to the right of the fitting 10. It will be understood that the fitting may be constructed with the elbow formation offset to the other side of the fitting, thus providing two fittings which otherwise are identical. Where the elbow formation 55 is offset, as illustrated in the drawings, with respect to the longitudinal axis of the fitting, the mouth of the projecting portion occupies a cross-sectional area so positioned with respect to the cross-sectional area of the fitting that a portion 60 of the liquid traveling through the fitting above and laterally of the bottom of the mouth of the projection will continue to travel uninterrupted in its normal path through the fitting. This will be clear upon reference to Figures 7 to 10.

When the fitting is being used for connecting the main supply pipe to a branch supply pipe, the portion 9 may be positioned vertically as 65 shown in Fig. 7 or may be turned at least 90° as illustrated in Fig. 9 and still maintain the inner end 20 located in the upper or hot water region of the main supply pipe. Of course, the portion 9 may be located at any position intermediate the position shown in Figs. 7 and 9 as illustrated in Fig. 8. Because of the fact that the fitting can 70 be used satisfactorily in so many different posi-

tions, a saving of piping and labor often results in given installations. It will be noted upon reference to Figures 2, 4 and 6 and 7 to 10 inclusive that the opening 20 defined by the wall 15 and the wall 18 forms an inlet for the branch which is 5 not substantially in excess of the quadrant of a circle defined by the radius of the bore of the fitting.

As shown in Fig. 10 the portion 9 is positioned in a horizontal plane and with the inner end 20 10 positioned in the lower or cold water region of the main supply pipe. This is the preferred position of the fitting for connecting the return pipe from the radiator to the main supply pipe in a hot water system where no pump or other type 15 of artificial circulator is employed. If a pump is employed then the main pipe may be positioned above a radiator and the return pipe extended upwardly and connected to the branch passage with the portion 9 in a vertical position. 20

One of the outstanding advantages of the fitting of the invention is that it makes possible an efficient one pipe hot water heating system either with or without a pump or other circulator. One reason for this efficiency is that the fitting 25 of the invention does not obstruct the flow of water inasmuch as the portion of the elbow formation which projects into the main passage of the fitting does not occupy a greater portion of the cross sectional area of the main passage than 30 the difference between the latter and the cross sectional area of the passage in the main supply pipe which is connected to the fitting. It will be noted upon reference to the drawings that the mouth of the projecting portion has a cross-sectional area of less extent than the area of the segment of a circle defined by a chord which passes through the innermost point of the mouth defining wall 15, i. e., the innermost point of projection of said wall into the bore. Another important reason for this efficiency is that hot water is withdrawn from a portion only of the hot water region of the fitting while permitting hot water to pass through the fitting in the remaining portion of the hot water region. Furthermore, cool 45 water is returned only to the cool water region of the main supply pipe. In this manner the hot and cool water regions are established and maintained in the main supply pipe. 35 40 45

The invention makes possible installations of 50 hot water heating systems at a cost not greater than that of steam heating installations. While it has been emphasized that the fitting of the invention is especially suitable for use in a one pipe hot water heating system without a pump, 55 it will be readily apparent that it is equally suitable for use in such systems with a pump or in two pipe hot water heating systems.

A modified type of fitting embodying the invention is shown in Figs. 11, 12 and 13 and comprises a body 11' having a passage 12' extending therethrough. The fitting is also provided with an elbow formation 14'. In these respects the fitting is identical to that previously described. In addition, the fitting is provided with a second 65 elbow formation 40 having a portion 41 extending laterally from the body 11' and having a wall portion 42 extending into the passage 12' so that its inner end 43 faces in the opposite direction from the inner end 20'. The fitting should be positioned so the elbow formation 14' is connected to the branch supply pipe and its inner end 20' is located in the upper or hot water region of the main supply pipe. The second 70 elbow formation 40 should be connected to the 75

return pipe and its inner end 42 located at the lower or cold water region of the main supply pipe. In certain cases it may be desirable to increase the diameter of the body 11' in the vicinity 5 of the elbow formations 14' and 40 so that the remaining portion of the cross sectional area in this region will not be less than the cross sectional area of the passage in the main supply pipe to which the fitting is connected.

10 I claim:

1. A reversible pipe fitting having a body for insertion in the main line of a liquid supply of a heat exchange system, said fitting having a lateral branch for establishing communication 15 with a branch line, the lateral branch having a portion projecting into the body, the mouth of said projecting portion defining a cross sectional area of less extent than the area of the segment of a circle defined by a chord which passes 20 through the innermost point of the mouth defining wall, said projecting portion occupying a position with relation to the fitting such as not to preclude that a portion of the liquid traveling through the zone in which the mouth of said projecting portion opens shall continue to travel in 25 its normal path of movement.

2. A reversible pipe fitting having a body for insertion in the main line of a liquid supply of a heat exchange system, said fitting having a lateral branch for establishing communication 30 with a branch line, the lateral branch having a portion projecting into the body, and the opening in said branch being not substantially in excess of the quadrant of a circle to direct liquid from 35 the fitting to the branch line or to return liquid from the branch line to the fitting in accordance with the position of the fitting, said projecting portion occupying a position with relation to the fitting such as not to preclude that a portion of 40 the liquid traveling through the zone of the fitting in which said projection opens shall continue to travel in substantially its normal path of movement.

3. A reversible pipe fitting having a body for 45 insertion in the main line of a liquid supply of a heat exchange system, said fitting having a lateral branch for establishing communication with a branch line, the lateral branch having a portion projecting into the body, said projection 50 having angularly disposed walls substantially of a length less than the radius of the bore of the fitting, whereby a by-pass alongside the projection for the free flow of the liquid is provided, the difference in cross sectional area between the 55 fitting in the plane of said projection and the

main line to which the fitting is connected being insufficient to substantially retard flow from the main line through the fitting.

4. A pipe fitting having a body for insertion in the main line of a liquid supply of a heat exchange system, said fitting having a lateral branch for establishing communication with a branch line and a second lateral branch for establishing communication with another branch line, each lateral branch having a projecting portion projecting into the body, the mouth of said projecting portion defining a cross sectional area of less extent than the area of the segment of a circle defined by a chord which passes through the innermost point of the mouth 15 defining wall, said projecting portions occupying positions with relation to the fittings such as not to preclude that a portion of the liquid traveling through the zone in which the mouths of said projecting portions open shall continue to travel 20 in its normal path of movement.

5. A reversible pipe fitting having a body for insertion in the main line of a liquid supply of a heat exchange system, said fitting having a lateral branch laterally offset with respect to the 25 longitudinal axis of the fitting for establishing communication with a branch line, the lateral branch having a portion projecting into the body, the mouth of the projecting portion occupying a cross-sectional area so positioned with 30 respect to the cross-sectional area of the fitting that a portion of the liquid traveling through the fitting above and laterally of the bottom of the mouth of the projection will continue to travel 35 uninterruptedly in its normal path through the fitting.

6. A reversible fitting having a body for insertion in the main line of a one pipe hot water heating system, said body having a lateral branch offset to one side of the center line of the 40 body, said branch having a wall projecting into the bore of the body and merging with the wall thereof and another wall disposed at an angle to the first wall and merging with the wall of the body, the wall of the fitting in the bore thereof 45 above said projection walls being shaped to form part of the wall of the branch and curved transversely and inclined longitudinally toward the outer end of the branch, the mouth opening defined by said walls being not substantially greater than the difference between the cross sectional areas of the main line and the bore of the fitting.

ANGELO MINELLA. 55
